(57) **CLAIM**

The ornamental design for a volatile dispenser, as shown and described.

DESCRIPTION

FIG. 1 is a top, right, frontal perspective view of the housing portion of the volatile dispenser wherein the refill cartridge has been removed for ease of illustration;

FIG. 2 is a right side elevational view thereof;

FIG. 3 is a left side elevational view thereof;

FIG. 4 is a front view thereof;

FIG. 5 is a rear view thereof;

FIG. 6 is a top plan view thereof;

FIG. 7 is a bottom plan view thereof;

FIG. 8 is a top, right, frontal perspective view of the volatile dispenser showing both the housing and refill cartridge;

FIG. 9 is a right side elevational view thereof;

FIG. 10 is a left side elevational view thereof;

FIG. 11 is a front view thereof;

FIG. 12 is a rear view thereof;

FIG. 13 is a top plan view thereof; and,

FIG. 14 is a bottom plan view thereof.

The broken line representations of plug and plug housing environment, a light array, grill holes, and a peel-off cover, are for purposes of illustration only, and form no part of the claimed design.
